UNITED STATES PATENT OFFICE.

HAROLD A. HALL, OF LOS GATOS, CALIFORNIA, ASSIGNOR OF ONE-HALF TO EARL C. FANCHER, OF SAN JOSE, CALIFORNIA.

INTERNAL-COMBUSTION ENGINE.

Application filed December 26, 1924. Serial No. 758,058.

To all whom it may concern:

Be it known that I, HAROLD A. HALL, a citizen of the United States, residing at Los Gatos, in the county of Santa Clara and State of California, have invented certain new and useful Improvements in Internal-Combustion Engines, of which the following is a specification.

My invention relates to internal combustion engines, and more particularly to a valve construction therefor.

The object of my invention is to provide means for assisting the cooling of the valves, and especially the exhaust valves, of an engine, thereby permitting higher compression and increased power and efficiency without danger of damage to the valves through overheating. Another advantage lies in the fact that the valves arranged according to the principles of my invention will operate, on account of their lower temperature, for a longer time without grinding or reseating, thereby reducing the cost of upkeep of the engine, and enabling it to be kept in service for a longer time without repair than is customary with engines of the present known types.

My invention will be described, and is herewith illustrated, as embodied in an engine of the T-head type having poppet valves, and as applied only to the exhaust valves thereof, but it is to be distinctly understood that the principles of the invention may be equally well applied, without material change, to engines of other types, or to the inlet as well as the exhaust valves, or even to engines having other types of valves. The embodiment of the invention herein disclosed has been chosen merely for purposes of illustration, with the understanding that changes, within the scope of the claims hereto appended, may be made in the form, construction, and arrangement of the parts without departing from the essential principles of the invention as expressed in said claims. As a matter of purely mechanical consideration, the exhaust valves of an engine are more subject to overheating than are the inlet valves, and for that reason my invention is shown as applied only to the exhaust valves, but it will be obvious that the inlet valves may be similarly arranged without requiring the exercise of more than ordinary mechanical skill.

With this in view, my invention will now be fully described with reference to the accompanying drawings, wherein—

Fig. 1 is a transverse section through one cylinder of an engine having my invention embodied therein. 60

Fig. 2 is a view, partly in section, of the exhaust valve mechanism of the cylinder shown in Fig. 1, and is taken on the line 2—2 thereof. 65

Fig. 3 is a sectional plan view taken on the line 3—3 of Fig. 1.

In the drawings, the reference numeral 1 designates the cylinder of an engine, which may be cooled in any well known manner, 70 as for example by a water jacket 1'. 2 is the piston operable in said cylinder, 3 is the crankshaft, 4 is the connecting rod, and 5 is the inlet valve for admitting gas or air to the cylinder 1 from the port 6. Said valve 5 is operated in the usual manner, being closed by a spring 7 and opened by a cam 8, the latter secured upon a cam shaft 9 and acting upon the valve through a tappet 10. 75

I provide a plurality of exhaust valves 11, two being shown in Figs. 2 and 3, for discharging the spent gases into a common port 12, Figs. 1 and 2. Said valves 11 are closed by springs 13 in the usual manner, and are opened, alternately, by cams 14 secured upon a cam shaft 15 and acting through tappets 16. 80

In a four-cycle engine, the inlet cam shaft 9 is rotated, as usual, at half the speed of the crank shaft 3, but the exhaust cam shaft 15 is rotated at quarter the speed of said crank shaft. Any well known means may be provided for driving the cam shafts 9 and 15 at the required speeds. For example, as shown in Fig. 1, said shafts may be provided with sprockets 17 and 18 respectively, and driven by a single chain 19 passing over a sprocket 20 upon the crank shaft 3. Obviously, the sprocket 17 must be twice the diameter of the crank shaft sprocket 20, and the sprocket 18 must be four times the diameter thereof. 95

The exhaust valve cams 14 are oppositely disposed upon their shaft 15, as shown in Fig. 2, so that only one of the exhaust valves 11 opens at each exhaust stroke of the cycle, the other of said valves remaining closed until the next exhaust stroke, when it opens and the first exhaust valve remains closed. By this arrangement there is one exhaust valve open at each exhaust stroke, but each 105 110

such valve opens only once in every two cycles. By remaining closed through practically one and three-quarter cycles (in a four cycle engine), each exhaust valve has 5 much greater opportunity to be cooled by contact with the relatively cool seat or cylinder casting, than is the case in the usual engine wherein each exhaust valve opens at every exhaust stroke, and therefore remains 10 seated only through three-quarters of the cycle.

As before stated, this increased cooling of the exhaust valves in an engine embodying my invention enables the use of a higher 15 compression, and also enables the engine to be operated longer without necessitating grinding the valves, than is the case in the usual type of engine.

I claim:

- 20 1. In an engine having a cylinder with a piston operable therein, said cylinder having a port for the passage of the impelling fluid; a plurality of valves for controlling said port; and means for operating said valves successively in timed relation to the piston movement.
- 25 2. In an engine having a cylinder with a

piston operable therein, said cylinder having an inlet port and an exhaust port; a plurality of valves for controlling one of 30 said ports; and means for operating said valves successively in proper timed relation to the movements of said piston.

3. In an engine having a cylinder with a piston operable therein, said cylinder having an exhaust port; a plurality of valves for controlling said port; and means for operating said valves successively, one such valve being opened at each exhaust stroke 35 of said piston.

4. In an engine having a cylinder with a piston operable therein, said cylinder having an inlet port and an exhaust port; a valve for controlling said inlet port; means for opening said valve at each intake stroke 40 of said piston; a plurality of valves for controlling said exhaust port; and means for operating said exhaust valves successively, one thereof being opened at each exhaust stroke 45 of said piston.

In testimony whereof I have signed my name to this specification.

HAROLD A. HALL.
